ADJUSTING MECHANISM FOR GRINDING-MILLS.

1,105,380.

Specification of Letters Patent.

Patented July 28, 1914.

Application filed January 10, 1911. Serial No. 601,924.

To all whom it may concern:

Be it known that we, HERBERT W. SPELLMAN and ERNEST TWIGG, citizens of the United States, both residing at New Britain, 5 in the county of Hartford and State of Connecticut, have invented certain new and useful Improvements in Adjusting Mechanism for Grinding-Mills, of which the following is a specification.

10 Our invention relates to improvements in adjusting mechanism for grinding mills for grinding coffee and the like, and the objects of our improvement are simplicity and economy of construction and to provide an indicator showing the degree of fineness to which the adjusting mechanism is set.

15 In the accompanying drawings: Figure 1 is a front elevation of our adjusting mechanism and so much of a grinding mill as is deemed necessary to show its connection therewith. Fig. 2 is a vertical section of some of the parts on the line $\alpha\alpha$ of Fig. 1, and a side elevation of the other parts. Fig. 3 is an enlarged sectional view on the line yy of Fig. 2. Fig. 4 is a front elevation of the major portion of that part of the case to which we apply the adjusting screw and indicator, the said screw and indicator being removed. Fig. 5 is a broken out rear elevation of the indicator.

20 A designates a portion of the case of a grinding mill, the said portion being hollowed out to receive the moving mill disk, not shown, while a bearing for the mill shaft 25 6, which is shown as broken off, is formed in the hub 7 of the said case A. This hub is counter bored and internally threaded to receive a mill adjusting screw 8, the inner end of which bears against a hard fiber disk 9 placed between the confronting ends of the 30 screw and shaft. The screw is provided with a knob 10 for convenience of operating the same. Turning the screw inwardly will force the shaft longitudinally inwardly and 35 thus carry the moving disk, which is mounted on the said shaft, toward the companion fixed disk and thus adjust the mill for finer grinding. Turning the screw in the reverse direction to unscrew it, will permit the shaft

and moving disk to move in the opposite direction to adjust the mill for coarser grinding, all substantially the same as in various mills of ordinary construction. 50

We improve the ordinary adjusting mechanism by the addition of certain parts 55 as follows: We provide the middle or body portion of the adjusting screw with a toothed gear or pinion 11 and the hub 7 of the case A with an upwardly extended bracket 12, the upper part of which bracket is bored 60 through from front to rear to form a bearing for the hollow indicator shaft or stud 13. This shaft carries a rotary indicator 14, the said indicator being provided with a toothed gear 14 for engagement with the gear or 65 pinion 11 of the screw 8. This indicator is of a larger diameter than the gear on the screw and has more teeth so that more than one revolution of the screw is necessary in order to turn the indicator one complete 70 revolution. The proportion should be such that one revolution of the indicator will require the screw to be moved longitudinally far enough to cover the entire range of the intended mill adjustment. As shown one 75 and a half revolutions of the screw is necessary to move the indicator a complete revolution and turning the screw this distance the entire range of adjustment intended for this mill is accomplished. The face of the 80 indicator has a circle of numbers thereon to indicate the degree of fineness to which the mill may be set. As shown these numbers run from 1 to 12, the lower numerals indicating a coarse set and the larger a fine set; 85 number one indicating the coarsest adjustment that will ever be required, while twelve indicates the finest that can be made. The indicator is covered and protected by a two part case, the front part 15 being cup shaped 90 to cover the front and main portion of the edge, while the rear part 16 covers the rear. The cup shaped front part is rigidly mounted on the front end of the hollow indicator shaft or stud, while the rear part is loosely 95 placed on the said stud with its edge shutting into the edge of the front part. In order to bring the teeth of the indicator in

engagement with the teeth on the screw and permit of placing and removing the indicator by a movement from front to rear in the longitudinal direction of the screw and 5 in the line of the indicator axis it is necessary to cut away the upper part of the hub at its front end as best shown at 17 in Fig. 4. This cut away portion is filled by a projection 18 of corresponding shape on the front 10 of the front part 15 of the indicator case and gives the said end of the hub its completed form. The lower edge of the indicator case is also cut away to clear the teeth on the screw as shown in Fig. 5. The indicator 15 and its case are held in place by a screw 19 inserted into the shaft or stud 13 from the rear of the bracket 12. In order to prevent an accidental movement of the indicator, we provide a frictional holder in the form of a 20 pin or plunger 20 and a spring 21, both of which are placed in a hole at the lower part of the bracket 12 with the outer rounded end of the plunger bearing on the rear sides of the indicator 14, a circle of cavities 22 being 25 formed in the said rear side immediately in front of the said plunger. A hole 23 is made through the back or rear part 16 of the indicator case to permit the front end of the plunger to pass therethrough. The 30 front part 15 of the case is provided with an index opening 24 through which to read the numbers on the indicator whenever they are presented thereto.

In order to properly set the indicator for 35 use the adjusting screw 8 is turned in the right hand direction to move it and the shaft 6 inwardly to the extreme limit of finest adjustment, that is until the mill disks are brought together. Then place the indicator 40 and its stud in position for insertion, the teeth of the indicator being in front of the front end of the pinion or gear 11 on the screw; set the indicator so that the number 12 is indicated through the index opening 45 and then move the indicator into place by a movement in the line of its axis and bring its teeth into engagement with the teeth of the pinion on the screw. The screw 19 may then be inserted to hold the parts in 50 place, and then, until reset, the number 12 at the index opening will indicate that the mill is adjusted for the finest grinding. As the adjusting screw is unscrewed to draw it outwardly, the numbers showing through 55 the index opening are successively smaller and indicate that the mill is set for coarser grinding. It will seldom, if ever, be necessary to move the adjusting screw outwardly far enough to have the indicator 60 show its first or smallest number.

By our improvement the user of the mill can tell at a glance whether the mill is adjusted for coarse or fine grinding, or how fine or how coarse when set at points be-

tween the two extremes. The construction 65 and arrangement are such that with the intended range of adjustment the indicator does not make more than one revolution and consequently will not indicate 12 or 11 or other fine adjustment for a coarse one. If, 70 however, the indicator should be turned more than one revolution in adjusting the mill for coarser grinding, that fact will be indicated by the outward position of the adjusting screw, so that any misreading would 75 not be likely to follow. By setting the indicator at 12 when the mill is adjusted for the finest grinding it will be impossible to turn the adjusting screw inwardly far enough to expose a small number on the indicator when the mill is adjusted for fine grinding.

The construction is simple, inexpensive and durable, and the indicator, although a great convenience to the user requires no 80 special attention or manipulation on his part other than to read the number presented to view.

We claim as our invention:

1. The arrangement and combination of 90 a case, an adjusting screw fitted in the said case, a driving gear mounted thereon and arranged for being set in a given position rotatively, an indicator comprising two parts one fixed and the other rotary, the 95 rotary part having a toothed gear for engagement with the said driving gear, guiding and supporting members for said indicator formed respectively in and on the said case and indicator and arranged for relatively sliding one upon the other in the longitudinal direction of the said screw, and a fastening device for securing the said indicator in position upon the said case; whereby the said driving gear and indicator 100 may each be separately set in a given position when the indicator is detached and then assembled properly by a sliding movement of the indicator on the said sliding and supporting members in the line of the 110 axis of the said adjusting screw.

2. The arrangement and combination of a main case, a driving gear mounted in the said main case and arranged for being set in a given position rotatively, a stud for 115 being mounted in a socket in said main case to one side of the axis of the said driving gear, an indicator case separate from the said main case and rigidly mounted on the said stud, and an indicator having a toothed gear rotatively mounted within the said indicator case for engagement with the said driving gear, whereby the said stud, indicator case and indicator may be completed separately from the said main case and 120 driving gear and applied thereto after completion.

3. The arrangement and combination of an

adjusting screw, a main case in which the said screw is mounted, a socket having a fixed relation to the said main case, a stud for being mounted in the said socket, an indicator case rigidly mounted on the said stud, an indicator having a toothed gear rotatively mounted within the said indicator case, and means for securing the said stud and connected parts within the said socket of the said case.
